Henry West
INVENTOR

UNITED STATES PATENT OFFICE.

HENRY WEST, OF OAKLAND, CALIFORNIA.

SIDENECKED DROPPING BOTTLE.

Application filed January 14, 1924. Serial No. 686,026.

To all whom it may concern:

Be it known that I, HENRY WEST, a citizen of the United States of America, residing in the city of Oakland, and county of 5 Alameda, and State of California, have invented a new and useful Sidenecked Dropping Bottle, of which the following is a specification.

My invention relates to the improvements 10 of a dropping bottle doing away with complicated mechanical adjustments; and the objects of my improvements are, first, to allow an easy passage for air to enter the bottle, second, to afford a simple adjustment 15 for controlling the size and number of drops of liquid and, third, to allow the bottle to be easily refilled or emptied, by pulling the cork out completely.

I attain these objects as illustrated in the 20 accompanying drawings in which:—

Figure 1, is a cross section of the bottle with cork partly removed.

Figure 2, is an outside view showing the 25 width of the liquid passage in the neck, by dotted lines.

Figure 3, is the same as Figure 1, except that the neck of the bottle is completely closed, by the cork.

Referring to the drawings in detail, 1, is 30 the bottle proper, made of glass or other suitable material, 2, is the liquid, 3, the cork or stopper, 4, the neck of the bottle, 5, a groove in the neck which allows the air to enter the bottle, 6, a groove opposite the air 35 groove, which allows the liquid to escape, 7, indicates drops of liquid.

By reference to Figures 1 and 3, it will be noticed that the bottle 1 is shown on a horizontal position and having a peculiar

shape, the neck 4 being curved up to one side or top; this is done so as the air will have a free passage into the bottle without being likely to come in contact with the liquid which in the case of an ordinary bottle causes, much bubbling.

Grooves 5 and 6, are cast into the bottle when made and, usually opposite, the approximate width is shown by the dotted lines in Figure 2. It will be noticed that these grooves 5 and 6 do not extend the full 50 length of the neck but a certain portion of the neck is left round to make a tight joint when the cork or stopper is inserted as shown in Figure 3.

I will now explain the operation.

The bottle as shown in Figure 3, is closed, to obtain a few drops, the cork 3 is pulled out slightly as in Figure 1, air enters into groove 5 while the liquid enters into groove 6, at a slow rate, going off into the form of 60 drops 7, if a larger drop or flow is wanted the cork can be pulled farther out, usually the cork will be held by friction, but if not the forefinger may be placed over the end of same, or cork may be pulled out entirely, 65 and used as an ordinary bottle.

Having thus described my invention, what I claim and desire to secure by Letters Patent is:

A bottle having its neck curved to one side other than its center, whereby the pressure of the liquid at the dropping surface is reduced, thereby obtaining a slow rate 70 of dropping, and having a groove or channel in its neck to admit air into the bottle, and also having a similar groove or channel in 75 its neck to permit liquids in the bottle to escape in combination with a cork.

HENRY WEST.
